Specification for Design.

Patented Sept. 24, 1918.

Application filed January 11, 1918. Serial No. 211,438. Term of patent 7 years.

To all whom it may concern:

Be it known that I, WILL RANSOM, a citizen of the United States, residing at Chicago, in the county of Cook and State of Illinois, have invented a new, original, and ornamental Design for a Font of Type, of which the following is a specification, reference being had to the accompanying drawing, forming a part thereof.

The drawing is a view of the characters of a font of type showing my new design.

I claim:

The ornamental design for a font of type, as shown.

WILL RANSOM.
